Fig. 8

Fig. 10

Fig. 11FIG. 1 is a front side elevational view of a time-indicating face for a horologe showing my new design;

FIG. 2 is a rear elevational view thereof;

FIG. 3 is a right side elevational view thereof;

FIG. 4 is a left side elevational view thereof;

FIG. 5 is an enlarged top plan view thereof;

FIG. 6 is an enlarged bottom plan view thereof;

FIG. 7 is a front side elevational view of a second embodiment of my new design wherein the shape is spheroidal rather than spherical;

FIG. 8 is a rear elevational view of FIG. 7;

FIG. 9 is a right side elevational view of FIG. 7;

FIG. 10 is a left side elevational view of FIG. 7;

FIG. 11 is an enlarged top plan view of FIG. 7.

The drawings are shaded for color contrast.

I claim:

The ornamental design for a time-indicating face for a horologe, as shown and described.
